CLAIM

The ornamental design for a corn hole light, as shown and described.

DESCRIPTION

FIG. 1 is a front side perspective view of a corn hole light;

FIG. 2 is a rear side perspective view thereof;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines show portions of the article which form no part of the claimed design.

1 Claim, 8 Drawing Sheets
